ICE FORMING AND ICE MELTING COOLING SYSTEM

Joseph I. Morrison, Lincolnwood, Ill.

Application February 8, 1949, Serial No. 75,265

16 Claims. (Cl. 62—141)

1

This invention relates to cooling systems and, more particularly, to a cooling system for use in a commercial dairy and the like where the cooling demand is variable. Because of the inherent characteristics of milk, it is necessary that upon receipt of the bulk milk at the cooling station it be cooled to approximately 40° F. in order to prevent deterioration of certain vitamins and other valuable ingredients contained in the milk. The bulk milk, upon being received, is separated and placed into convenient cans or receptacles which, in turn, are placed in a cooling tank where the temperature of the milk is lowered to the required 40° F. The milk is held at this temperature until it is ready for further processing. Examples of cooling systems of this type are disclosed in my Patent No. 2,448,433, dated August 31, 1948, and my pending application, Serial No. 68,198, filed December 30, 1948.

It is one of the objects of this invention to provide a cooling system which is relatively small in size, yet has a highly efficient heat-absorbing operation.

A further object of my invention is to provide a liquid-freezing and ice-melting apparatus in which the flow control and cross-sectional area of the flow passage will remain substantially unchanged regardless of the thickness of ice deposited on the confining walls of the passage, in which the length of flow will increase as the ice is melted and in which turbulence of flow is created to bring all parts of the flowing fluid into contact with the ice formation to increase the speed of melting of the ice.

It is a further object of this invention to provide a cooling system which causes the liquid circulating throughout the system to become turbulent when adjacent the cooling coils or pipes and thereby effectuate greater heat transfer from the circulating liquid.

It is a further object of this invention to provide a cooling system which is simple and compact in construction, effective and efficient in operation, and inexpensive to produce.

Further and additional objects will appear from the description, the accompanying drawings, and the appended claims.

In accordance with one embodiment of this invention, a cooling system is provided comprising a reservoir, a refrigerator therefor, and a cooling tank operatively connected to said reservoir. Mounted within the reservoir are a plurality of spaced baffle members. The refrigerator comprises a plurality of refrigerant-receiving and heat-absorbing assemblies; one of said as-

2

semblies being mounted on each of said baffle members. Mounted on either face of the baffle members and extending therefrom in an angular direction into the space formed intermediate adjacent baffle members are a plurality of fin-like members. The fin-like members cause the liquid circulating between the baffle members to become turbulent and thereby effect greater heat transfer from the liquid to the assemblies mounted on the adjacent baffle members.

For a more complete understanding of this invention, reference should be made to the drawings wherein

Figure 1 is a fragmentary, sectional, side elevational view of the preferred form of reservoir;

Fig. 2 is a fragmentary, sectional, top plan view of the reservoir taken along line 2—2 of Fig. 1;

Fig. 3 is an end view of the reservoir shown in Fig. 1;

Fig. 4 is a fragmentary, sectional, side elevational view of a modified form of reservoir;

Fig. 5 is a fragmentary, sectional, side elevational view of the modified form of reservoir taken along line 5—5 of Fig. 4;

Fig. 6 is an enlarged, fragmentary, perspective view of one of the baffle members mounted within the reservoir shown in Fig. 1;

Fig. 7 is a diagrammatic view showing the direction of flow of the circulating liquid in the reservoir shown in Fig. 1;

Fig. 8 is an enlarged, fragmentary, sectional view of one of the baffle members of the reservoir shown in Fig. 4 showing the formation of the congealed liquid thereon, and

Fig. 9 is similar to Fig. 8 but shows the congealed liquid partially melted away by the circulating liquid.

Referring now to the drawings and, more particularly, to Figs. 1 and 2, a reservoir 10 of the preferred type is shown, which is operatively connected by suitable conduits 12 and 14 to an adjacent cooling tank, not shown. Intermediate the cooling tank and reservoir 10 is provided a suitable pump (see 10a, Fig. 5) for circulating a cooling liquid through the reservoir and cooling tank.

Mounted within the reservoir 10 are a plurality of parallel, vertically-extending, spaced baffle members 16 and 18, and a transversely mounted baffle member 20 dividing baffle members 16 and 18 into substantially equal sections 16a, 16b, 18a, and 18b. The baffle members 16, 18, and 20 are so arranged within the reservoir as to cause the direction of flow of the circulating liquid to be like that shown in Fig. 7.

The relatively warm liquid from the cooling tank enters the reservoir through conduit 12 and first passes, as shown in Figs. 2 and 7, between the side 21 of the reservoir and baffle member 18a and, upon reaching the terminating edge 22a of member 20, which is spaced from the end plate 23 of the reservoir, is directed downwardly and flows in the opposite direction between side 21 and baffle member 18b; on reaching the edge 24 of member 18b, which is spaced from the end plate 25 of the reservoir, the liquid turns about edge 24 and flows in the opposite direction between baffle members 16b and 18b; on reaching the edge 22b of baffle member 20, the liquid is directed upwardly and flows in the opposite direction between baffle members 16a and 18a; upon reaching the terminating edge 26 of baffle member 16a, which is likewise spaced from end plate 25, the liquid reverses direction and flows between side 21 of the reservoir and baffle member 16a; at terminating edge 22c of member 20, the liquid once again is directed downwardly and flows in the opposite direction between side 21 and baffle member 16b and out through conduit 14 to the cooling tank, not shown. By following this tortuous passage through the reservoir, the circulating liquid is able to expend a sufficient amount of heat to readily meet the variation in cooling demand.

A refrigerator 28 is provided for the reservoir having a plurality of refrigerant-receiving and heat-absorbing assemblies 30 and 32. Assembly 30 is mounted on one surface of baffle members 16a and 16b, and assembly 32 is mounted on a corresponding surface of baffle members 18a and 18b. In this instance, each assembly comprises banks of coils integrally connected to one another and each assembly 30 and 32 serves as a refrigerator for baffle members 16a, 16b, and 18a, 18b, respectively. The refrigerant supply, means for circulating the refrigerant through the coils, and the compressor for the refrigerator are of standard construction and well known by those skilled in the art and, therefore, further description as to their operation is deemed unnecessary. The refrigerant, which may be ammonia, sulphur dioxide, etc., is introduced, as shown by arrow A, Fig. 3, into the cooling coils 30 and 32 in a liquid form from the expansion valve, not shown, through conduits 34 and 35, respectively, and is removed from the coils, as shown by arrow B, in a gaseous state at conduits 36 and 37, respectively, to the compressor, not shown.

The sides 21 and 27, end plates 23 and 25, and the base 38 of the reservoir are of water-tight, insulated construction. Mounted on either face of the baffle members 16a, 16b, 18a, and 18b, and on the inner surfaces of sides 21 and 27 of the reservoir are a plurality of fin-like members 40. These members 40 are constructed of relatively thin, rigid material, such as sheet metal, and as shown in Figs. 1 and 6, are of rectangular shape. It is to be understood, of course, that members 40 are not to be limited to this particular shape. The members 40 are spaced from one another along the surface of the baffle members 16a, 16b, 18a, and 18b, and extend in substantially a vertical direction. The vertical plane of the members 40 are offset approximately 30° with respect to the adjacent baffle member to which they are secured.

It is to be noted that, on one side of the baffle members, the assembly or coils are disposed intermediate the fin-like members 40 and the adjacent baffle member. Suitable brackets 42 hold

the outer edge 44 of the members 40 away from the adjacent coils and baffle members so that the edge 44 points in a direction substantially contra to the direction of flow of the circulating liquid thereby causing turbulence of the liquid to occur. Because of such turbulence, greater heat is transferred from the liquid to the coils resulting in an increase in the efficiency of the system. The inner edges 46 of the members 40 are secured to the adjacent coils or surface of the baffle member, depending on which side of the baffle member they are placed, by welding or any other suitable means.

In the modified form of reservoir 48, shown in Figs. 4 and 5, the flow of the circulating liquid is substantially in a vertical plane rather than a horizontal plane as for reservoir 10. In place of the cooling coils of reservoir 10 there are provided in reservoir 48 a plurality of vertically extending conduits 50, secured at either end to headers 51 and 52. The lower header 52 is supplied with a refrigerant in a liquid state from a container 54, mounted along the upper side of the reservoir above header 51, by means of a vertically extending supply conduit 56. The upper header 51 receives the refrigerant in a gaseous state after it has passed from the lower header 52 up through conduits 50. From the upper header 51, the gaseous refrigerant is passed through a compressor, condenser, and expansion valve, none of which are shown, and transformed back into a liquid state and returned to container 54 where the cycle will again be repeated. The liquid refrigerant supplied to lower header 52, through conduit 56, is controlled by a conventional float valve 57 mounted within container 54.

Mounted within the modified form of reservoir 48 are a plurality of spaced, vertically-extending baffle members 58 and a single vertically-extending baffle member 60 having its vertical plane at a right angle to that of the spaced baffle members 58 and adapted to separate said members 58 into substantially equal sections. The arrangement of baffle members 58 and baffle member 60 causes the circulating liquid to flow in a substantially vertical plane and alternately from one section of baffle members to the other. The vertical conduits 50 and 56 and headers 51 and 52 are secured to one side of baffle members 58, as seen in Fig. 5.

As in reservoir 10, plurality of fin-like members 62 are mounted on either side of baffle members 58 and angularly extend therefrom into the space formed intermediate adjacent baffle members. The fin-like members extend from the baffle members so that they are pointing in a direction substantially contra to the flow of the circulating liquid and likewise cause turbulence of said liquid, thereby increasing the heat transfer from the liquid to the refrigerant circulating in the vertical conduits 50.

When the demand on the cooling system is small, that is to say, when the aforementioned cans or receptacles are removed from the cooling tank, the amount of heat carried by the circulating liquid is small resulting in the liquid adjacent the vertical conduits 50 congealing, as shown in Fig. 8. Upon increase of the demand of the cooling system, the circulating liquid, as indicated by arrow 64, Fig. 9, causes the congealed liquid to gradually melt away, thereby effecting greater cooling of the circulating liquid. The liquid circulating in reservoir 10 also congeals about the cooling coils and between the adjacent fins when the cooling demand is reduced. The water circulation between the reservoir 48

and the cooling tank 65 is from the reservoir through the pipe 66 to the tank and from the tank through the pump 10a and pipe 67 to the reservoir 48. In general, when the cans are in the tank 65, ready to be cooled by the cooling water from the melting ice in the reservoir, the supply of refrigerant to the cooling coils in the reservoir is discontinued. The pump 10a is started to effect circulation of water through the tank 65 and through the passages between the baffles 16, 18, and 20. At the beginning of the circulation of cooling water, the ice formation on the baffles may be substantially as shown in Fig. 8, in which the general plane of the ice exposed to the circulating water is substantially flush with the plane of the outer edges of the fins 62. Under these conditions the flow through the passages between the baffles is comparatively unimpeded and not subjected to great turbulence. This smooth, uninterrupted, nonturbulent flow would continue as the ice continued to melt were it not for the turbulence-creating flow-obstructing fins 62. Without these fins the effective cross section of the passages between the ice formations would increase as the ice melted, with a consequent decrease of the speed of flow since the volume of flow effected by the pump 10a would remain constant. With the turbulence-creating flow-obstructing fins functioning, the effective cross-sectional area of the flow channels is not changed by the melting of the ice as the ice-melting water has to flow through the bottle-necks between the adjacent edges of opposed fins projecting from the baffles. Furthermore, as the ice melts, the length of the ice surfaces between which the ice-melting water has to flow increases, as shown in Fig. 9. Fig. 9 shows how the ice-melting water melts the water in the form of pockets between the fins, thus increasing the extent of surface of the exposed ice. These pockets also create turbulence which causes all parts of the ice-melting water to come in contact with the ice to be melted. The ice-melting is much faster when these fins are used than when they are not used, due to the increased speed of flow of the ice-melting water along the exposed ice surfaces and due to the turbulence of the water created by the fins. Without these fins the water would flow in a sort of layer formation between the smooth exposed ice surfaces, the layers of water adjacent the ice giving up their heat to melt the ice but the remote layers not having this opportunity.

Thus it will be seen that a cooling system has been provided which effectively handles variable cooling demands and has a greater heat-transferring efficiency because of the turbulence of the circulating liquid created by the fin-like members mounted on the baffle members.

While several embodiments of this invention are shown above, it will be understood, of course, that the invention is not to be limited thereto, since many modifications may be made, and it is contemplated, therefore, by the appended claims, to cover any such modifications as fall within the true spirit and scope of this invention.

I claim:

1. A cooling system comprising a reservoir having a plurality of spaced baffle members mounted therein, a cooling tank operatively connected to said reservoir, means for circulating a common liquid through said reservoir and tank, a refrigerator for said reservoir having a refrigerant-receiving and heat-transferring assembly juxtaposed said baffle members, and fin-like members

mounted on said baffle members and extending into the space formed intermediate adjacent baffle members and extending substantially across the width of the flow stream to restrict the thickness of the flow stream whereby the melting of the ice will not materially change the effective cross-sectional area of the flow stream.

2. A cooling system comprising a reservoir having a plurality of spaced baffle members mounted therein, a cooling tank operatively connected to said reservoir, means for circulating a common liquid through said reservoir and tank, a refrigerator for said reservoir having a refrigerant-receiving and heat-absorbing assembly provided with extensive heat-absorbing surfaces mounted on said baffle members, and fin-like members projecting outwardly from said baffle members into the space formed intermediate adjacent baffle members and extending substantially across the width of the flow stream to restrict the thickness of the flow stream whereby the melting of the ice will not materially change the effective cross-sectional area of the flow stream.

3. A cooling system comprising a reservoir having a plurality of spaced baffle members mounted therein, a cooling tank operatively connected to said reservoir, means for circulating a common liquid through said reservoir and tank, a refrigerator for said reservoir having a refrigerant-receiving and heat-absorbing assembly provided with extensive heat-absorbing surfaces mounted on each of said baffle members, and fin-like members mounted on either side of said baffle members and angularly extending therefrom into the space formed intermediate adjacent baffle members and extending substantially across the width of the flow stream to restrict the thickness of the flow stream whereby the melting of the ice will not materially change the effective cross-sectional area of the flow stream.

4. A cooling system comprising a reservoir having a plurality of spaced baffle members mounted therein, a cooling tank operatively connected to said reservoir, means for circulating a common liquid through said reservoir and tank, the spacings between adjacent baffle members being serially connected and providing a tortuous passage for said circulating liquid in said reservoir, a refrigerator for said reservoir having a plurality of refrigerant-receiving and heat-absorbing assemblies juxtaposed said baffle members and provided with extensive heat-absorbing surfaces, and fin-like members disposed in said tortuous passage and offset with respect to said baffle members and extending substantially across the width of the flow stream to restrict the thickness of the flow stream whereby the melting of the ice will not materially change the effective cross-sectional area of the flow stream.

5. A cooling system comprising a reservoir having a plurality of elongated, spaced baffle members attached at one edge to the sides of said reservoir, a cooling tank operatively connected to said reservoir, means for circulating a common liquid through said reservoir and tank in substantially a horizontal direction, a refrigerator for said reservoir having a plurality of refrigerant-receiving and heat-transferring assemblies juxtaposed said baffle members, and a plurality of fin-like members interposed said baffle members and extending substantially across the width of the flow stream to restrict the thickness of the flow stream whereby the melting of the ice will not materially change the effective cross-sectional area of the flow stream.

6. A cooling system comprising a reservoir having a plurality of elongated, substantially parallel, spaced baffle members mounted therein, a cooling tank operatively connected to said reservoir, means for circulating a common liquid through said reservoir and tank, a refrigerator for said reservoir having a plurality of refrigerant-receiving and heat-absorbing assemblies mounted on said baffle members, said assemblies adapted to receive a refrigerant for congealing the liquid adjacent thereto, and fin-like members interposed said baffle-members and offset with respect thereto and extending substantially across the width of the flow stream to restrict the thickness of the flow stream whereby the melting of the ice will not materially change the effective cross-sectional area of the flow stream.

7. A cooling system comprising a reservoir having a plurality of baffle members mounted therein; a cooling tank operatively connected to said reservoir; means for circulating a common liquid through said reservoir and tank; a refrigerator for said reservoir comprising a source of refrigerant, a refrigerant-receiving and heat-absorbing assembly juxtaposed said baffle members, and means for circulating said refrigerant through said assembly; and fin-like members interposed said baffle members and offset with respect thereto and extending substantially across the width of the flow stream to restrict the thickness of the flow stream whereby the melting of the ice will not materially change the effective cross-sectional area of the flow stream, said assembly adapted to congeal the liquid adjacent thereto.

8. A cooling system comprising a reservoir having a plurality of spaced baffle members alternately secured at one edge to opposite sides of said reservoir, a cooling tank operatively connected to said reservoir, means for continuously circulating a liquid through said reservoir and tank, the flow of said liquid in said reservoir being substantially transverse relative to sides thereof, a refrigerator for said reservoir having a refrigerant-receiving and heat-absorbing assembly mounted on one face of said baffle member and covering substantially the entire area thereof, and a plurality of fin-like members mounted on either face of said baffle members and extending outwardly therefrom in an angular direction substantially opposed to the direction of flow of said circulating liquid and extending substantially across the width of the flow stream to restrict the thickness of the flow stream whereby the melting of the ice will not materially change the effective cross-sectional area of the flow stream.

9. A cooling system comprising a reservoir having two sets of spaced, vertically extending baffle members mounted therein, one disposed above the other; a transversely mounted baffle member interposed said sets; a cooling tank operatively connected to said reservoir; means for circulating a liquid through said reservoir and tank and common to both; the flow of said liquid in said reservoir being tortuous and passing alternately through said upper and lower sections; a refrigerator for said reservoir having a plurality of refrigerant-receiving and heat-absorbing assemblies mounted on said baffle members; and a plurality of fin-like members mounted on either face of said baffle members for effecting turbulent flow of said liquid therebetween and extending substantially across the width of the flow stream to restrict the thickness of the flow stream whereby the melting of the ice will not materially change

the effective cross-sectional area of the flow stream.

10. A cooling system comprising a reservoir having a plurality of equi-spaced, vertically extending baffle members, and a transversely mounted baffle member separating said vertically extending baffle members into substantially equal sections; a cooling tank operatively connected to said reservoir; means for circulating a common liquid through said reservoir and tank; the flow of the liquid in said reservoir being tortuous and alternately through said sections; a refrigerator for said reservoir having a refrigerant-receiving and heat-absorbing assembly mounted on one surface of each of said vertical baffle members and covering substantially the area of said surface; and fin-like members mounted on said baffle members and angularly extending therefrom into the space formed intermediate said adjacent baffle members and extending substantially across the width of the flow stream to restrict the thickness of the flow stream whereby the melting of the ice will not materially change the effective cross-sectional area of the flow stream; said assembly adapted to receive a refrigerant for congealing the circulating liquid adjacent thereto.

11. A freezing and ice-melting cooling apparatus comprising two juxtaposed refrigerant-receiving and heat-transferring devices, each provided with an extensive heat transfer surface, said surfaces being substantially parallel to each other, and means for causing a flow of congealable liquid in the passage between said surfaces, whereby the liquid may be congealed on said surfaces by the refrigerant and may be melted therefrom by the flow of the liquid, each surface being provided with a series of substantially parallel flow barriers extending substantially across the width of the flow stream and extending from said surface toward the other surface to restrict the thickness of the flow stream, whereby as the ice melts the effective cross-sectional area of the flow stream will not be changed materially.

12. A freezing and ice-melting cooling apparatus comprising two juxtaposed refrigerant-receiving and heat-transferring devices, each provided with an extensive heat transfer surface, said surfaces being substantially parallel to each other for causing a flow of congealable liquid in the passage between said surfaces, whereby the liquid may be congealed on said surfaces by the refrigerant and may be melted therefrom by the flow of the liquid, each surface being provided with a series of substantially parallel flow barriers extending substantially across the width of the flow stream and extending from said surface toward the other surface to restrict the thickness of the flow stream, whereby as the ice melts the effective cross-sectional area of the flow stream will not be changed materially, said barriers being shaped to provide pockets opening toward the oncoming flow of liquid, whereby as the ice in the pockets melts, the exposed ice surface will increase in extent.

13. A freezing and ice-melting cooling apparatus comprising two juxtaposed refrigerant-receiving and heat-transferring devices, each provided with an extensive heat transfer surface, said surfaces being substantially parallel to each other for causing a flow of congealable liquid in the passage between said surfaces, whereby the liquid may be congealed on said surfaces by the refrigerant and may be melted therefrom by the flow of the liquid, each surface being provided with a series of substantially parallel flow barriers ex-

tending substantially across the width of the flow stream and extending from said surface toward the other surface to restrict the thickness of the flow stream, whereby as the ice melts the effective cross-sectional area of the flow stream will not be changed materially, the barriers on two surfaces being opposite each other, whereby they co-operate to define the effective flow area.

14. A freezing and ice-melting cooling apparatus comprising two juxtaposed refrigerant-receiving and heat-transferring devices, each provided with an extensive heat transfer surface on each face, said surfaces being substantially parallel to each other for causing a flow of congealable liquid in the passages along and between said surfaces, whereby the liquid may be congealed on said surfaces by the refrigerant and may be melted therefrom by the flow of the liquid, each surface being provided with a series of substantially parallel flow barriers extending substantially across the width of the flow stream and extending from said surface toward another surface to restrict the thickness of the flow stream, whereby as the ice melts the effective cross-sectional area of the flow stream will not be changed materially.

15. A freezing and ice-melting cooling apparatus comprising two juxtaposed refrigerant-receiving and heat-transferring devices, each provided with an extensive heat transfer surface, said surfaces being substantially parallel to each other for causing a flow of congealable liquid in the passage between said surfaces, whereby the liquid may be congealed on said surfaces by the refrigerant and may be melted therefrom by the flow of the liquid, each surface being provided with a series of substantially parallel flow barriers extending substantially across the width of the flow stream and extending from said surface

toward the other surface to restrict the thickness of the flow stream, whereby as the ice melts the effective cross-sectional area of the flow stream will not be changed materially, a cooling tank, and means for causing a flow of liquid from said passage to said tank and from said tank to said passage.

16. A freezing and ice-melting cooling apparatus comprising a refrigerant-receiving and heat-transferring device provided with an extensive heat transfer surface, a flow guide having an extensive liquid flow guide surface parallel to said heat transfer surface, and means for causing a flow of congealable liquid in the passage between said surfaces, whereby the liquid may be congealed on said heat transfer surface by the refrigerant and may be melted therefrom by the flow of the liquid, said heat transfer surface being provided with a series of substantially parallel flow barriers extending substantially across the width of the flow stream and extending from said heat transfer surface toward the other surface to restrict the thickness of the flow stream, whereby as the ice melts, the effective cross-sectional area of the flow stream will not be changed materially.
